THERMIONIC TUBE

Application filed May 6, 1925. Serial No. 28,401.

REISSUED

This invention relates to thermionic tubes such as are employed in the reception, detection and amplification of radio messages and also in telephone repeating and amplification, and other instances of amplification and magnification of electrical impulses. The customary mode of generating negative electrons is to use a metallic filament heated electrically, and it has always heretofore been necessary to employ an absolutely steady direct current for this purpose since any variation in the current caused similar variations in the reception wires. Thus the employment of alternating current produced a hum which obliterated all signals, and the customary mode heretofore followed has been to energize the emitting filament by the use of a primary or storage battery. The object of the present invention is the provision of a tube of this character which can be connected directly to an alternating current supply of the requisite voltage and which will exhibit the same mode of operation as with a direct current source, entirely without humming sounds or other noises; the provision of a new arrangement of filaments whereby variations in direction and potential of the current flow may be neutralized; while other objects and advantages of the invention will become apparent as the description proceeds.

In the drawings accompanying and forming a part of this application I have shown specimen modes of applying my invention to a standard tube of one of the most widely known makes although it will be understood that I do not limit myself to kind, appearance, or type of tube and have chosen this solely for purposes of illustrating the essential idea of my invention without restricting myself to the arrangement shown. Fig. 1 is a perspective view of a tube of the type described, portions of the elements being broken away in order to show the internal construction; Fig. 2 is an enlarged view of the filament and support, the plate and grid being entirely omitted; Figs. 3, 4, and 5 are detail views showing other arrangements of filaments; and Figs. 6 and 7 are detail views

showing concentrated forms of filaments as desired for certain other types of tubes.

Practically all tubes comprise an evacuated glass globe 1, a supporting base 2, and certain metallic elements enclosed within the tube and comprising in one guise or another, a plate 3, grid 4 and filament 5, 6. Ordinarily this filament consists of a single circuit but according to my invention I make said filament of even numbers of plural strands located close together and connected between the terminals of the alternating current in reversed positions, the filaments being so arranged as regards other elements that the electrostatic condition created by one filament shall be neutralized by the other filament, with the result of producing a steady source of negative electrons.

Thus, in the form shown in Figs. 1 and 2 the various wires are brought into the tube through a press 7 in which numerous wires are sealed such as the wires 8-8 which carry the plate, the wires 9-9 which carry the grid and the connections 10, 11, which carry filaments. The connection 10, in addition to receiving the lower end of the filament 5 also carries a bracket 12 terminating at its upper end in a hook 13 which supports the upper end of the companion filament 6. Likewise the connection 11 carries a bracket 14 which terminates at its upper end in a hook 15 to which is secured the upper end of the filament 5. Preferably in practice these brackets 12 and 14 are located outside of the tube elements as shown in Fig. 1. The filament and elements are connected to base contacts in the usual manner and in use the wires 10, 11 are connected to opposite ends of the secondary winding 16 of a transformer 17 whose primary winding 18 is connected to any suitable supply of alternating current such as the ordinary lighting circuit. Any suitable or desired voltage may be employed although I have been particularly successful with the use of a rather large current and small voltage, the latter about $\frac{1}{2}$ to 1 volt. This has the further advantage of enabling the use of heavier and stronger filament wires than can be used in higher voltages.

If we assume at any given instant that the

wire 10 is positive and the wire 11 negative, due to the fluctuations in the circuit, then the lower end of the filament 5 will be positive and the lower end of the filament 6 negative and at the same time, owing to the fact 5 that the brackets 12 and 14 have substantially a zero resistance the upper end of the filament 6 is positive. In other words the A. C. wave starts simultaneously at opposite ends of the two filaments, and as the wave progresses, it progresses exactly the same in both filaments, that point which was before highly positive gradually decreasing and that point which before was highly negative gradually 10 approaching positive until the two reach the same condition, which occurs midway of the wave, after which the lower end of the filament 5 becomes increasingly negative and the lower end of the filament 6 increasingly 15 positive. Considered in another aspect it can be pictured that alternating waves are constantly chasing each other up and down the respective filaments but are so related, one to the other, that the algebraic sum of 20 such waves at equal horizontal levels in the respective filaments is always zero. This is readily seen at the instant of highest potential in one of the filaments, at which time the corresponding point in the other filament 25 exhibits its correspondingly low potential, and if these filaments are sufficiently close together the electrostatic charge on the one exactly equals that on the other; and is likewise true when as a result of the advance of 30 a wave given point of one filament becomes zero relative to outside standards, at which instant the corresponding point of the other filament should always exhibit zero potential. As a result both wires are always 35 maintained under sufficient temperature to produce an adequate supply of electrons, without at the same time causing the alternating current of the lighting systems to influence the reception since a positive condition at each point of each filament is exactly counterbalanced by an equivalent negative on the nearest segment of the companion filament.

These filaments may be supported and looped in a great many modes without departure from the scope of my invention or avoiding this mode of operation. The arrangement illustrated in Figs. 1 and 2 is in many ways the simplest and most practical. However, it is equally possible whenever desired to increase the number of filaments as for example by making them in small segments as shown in Fig. 3 in which case the wires 10^a and 11^a are provided with brackets 13^a, 13^b, 15^a, 15^b respectively adapted to support the segments 5^a—5^a and 6^a—6^a, the lower ends of the segments being suitably connected to the other wires to which their respective upper ends were attached.

Another mode of arrangement is shown in

Fig. 4 wherein the filaments 5^b and 6^b are connected at their upper and bottom ends to the wires 10^b and 11^b, these filaments being made of any suitable material. In the form of the invention shown in Figs. 1 and 2 I have 70 shown tungsten wires. These may, if desired, have their emissivity increased by a coating of refractory earths such as thoria, and the greater thickness of the filaments as in Fig. 3 is intended to indicate this. In Fig. 75 4 I have shown these filaments as consisting of thin strips or ribbons of nickel, which also may, if desired, be treated superficially to increase the emissivity. In this case it is not necessary to keep the filaments apart at the center since this point always exhibits equal potential on the two filaments. In the form shown in Fig. 5 the filaments instead of making only one connection between the wires 10^c and 11^c are looped back and forth repeatedly. The forms shown in Figs. 6 and 7 are 80 devised for a more concentrated arrangement. In Fig. 6 the supporting wires 10^d and 12^d are crossed but insulated from each other at the center, their extremities being 85 surrounded by filaments 5^d, 6^d here making a complete parallelogram; and in Fig. 7 the filaments 5^e, 6^e are shown as wound together into a double spiral, the ends being connected to the terminals 10^e, 11^e.

It is not important whether the filaments 90 5 and 6 be parallel to each other as they appear to be in Fig. 2 or somewhat inclined as in Figs. 1, 4, and 5, provided only that they be substantially parallel to the face of the 95 anode and that they be symmetrical with respect to a straight line which is parallel to the face of said anode. This axis of symmetry may either be vertical as in the form of Fig. 1 or transverse as in Fig. 5. Indeed 100 in Figs. 4, 5, and 6 there are two rectangular axes of symmetry.

I have described the condition I have 105 sought and here obtained by the expression that the electrostatic effect produced by one 110 filament is neutralized by another filament, or that the combined, external, electrostatic effect of those filaments is zero. This concept possibly requires additional elucidation. It is the purpose of my invention to obtain 115 thermal emission of negative electrons by the use of an alternating current. It has been known for many years that electrons are 120 driven off a metallic body by heating it. If the body be insulated from other bodies the number of electrons that can be removed is 125 comparatively small since the abstraction of each negative charge leaves a corresponding positive charge on the body which tends to pull the negative charges back. In case the accumulated positive charge thus developed on the heated body be neutralized or discharged in any way more electrons are freed. This can be done by attaching the body to the 130 negative pole of a high potential battery such

as the "B battery" used in radio work, especially if the other pole of the same battery be brought sufficiently near to receive the negative electrons so emitted.

When an electric current is used to heat the body a second set of electrons is employed at the same time, the hypothesis being that this current is merely the passage of a different set of electrons through the body, and the heating effect a symptom of resistance to the passage of those electrons. Although the two currents traverse the same body, namely the current which causes the heat and the current which causes the electronic emission, they are entirely separate and distinct and independent. It is hardly believed that the individual electrons which enter with the heating current always escape with that current and vice versa any more than the individual drops of water that enter a reservoir through two pipes leave that reservoir through any given pipes. Presumably the electrons are devoid of individuality so that it is merely requisite that the same number per second leave the body over the respective circuits as entered it by those circuits, but as long as the heating circuit is uniform in potential its electrostatic effect can be ignored.

Now if the potential of either circuit be varied, the rate of electronic emission must likewise vary. If the B battery be removed or made more feeble the number of electrons which can be released is likewise reduced; and if the body be heated by an alternating current its potential constantly in accordance with the phase of the E. M. F. will vary and ordinarily tends to influence the electron emission in like proportion. It is for the purpose of neutralizing this effect that I employ plural bodies (in this case the filaments 5, 6,) so arranged that when a given point of one shall be positive the corresponding point of the other shall be negative. This is expressed briefly by the statement that the combined electrostatic effect of the two bodies (filaments) is zero.

It appears not to be necessary that the two bodies be so close together at every point as to effect such neutralization at every point; indeed it is arguable that this condition might cause the one which chanced momentarily to be positive to absorb all the electrons emitted at that instant by the other body. It is only necessary that their combined electrostatic effect upon adjacent bodies or elements as a whole should be neutralized, leaving the heating effect free to release the electrons in the same manner as in the case of any other mode of heating. The fact that the result in view can be obtained by any one of the various arrangements of filaments shown herein indicates that it is the total summation effect which is important and not the detailed effect at given points. This fact further in-

dicates that numerous other detailed arrangements of filaments and elements can be employed with successful results, wherefore I do not restrict myself to the arrangements, or designs, or connections herein shown, nor in any other manner except as recited in my several claims.

Having thus described my invention what I claim is:

1. A thermionic tube having plate and grid elements therein, an even number of filaments, and connections for conveying a heating current to said filaments, the latter being so arranged that each has a part lying substantially alongside a neighboring filament, and the connections being so arranged that the instantaneous direction of flow in such parts of the two filaments is substantially opposite.

2. A cathode structure comprising a plurality of parallel non-contiguous filaments each having terminals and supporting members connected thereto adapted to conduct energy to the said filaments, adjacent terminals of the said filaments being connected to supporting members of opposite polarity.

3. A thermionic tube having therein an anode and a cathode structure and having external anode- and cathode-terminals and terminal provisions for a cathode-energizing circuit, said cathode-structure comprising resistance wire connected between said terminal provisions, each portion of such resistance wire being adjacent to but out of contact with another portion of such resistance wire, which exhibits at every instant an opposite electric polarity from the first-named portion, whenever said terminal provisions are connected in circuit with a source of alternating electric current, whereby external field effect of the cathode-heating current is neutralized.

4. A thermionic tube having therein a plate, a grid, and a cathode, said cathode comprising terminals and a filamentary structure connected between said terminals and comprising adjacent non-contiguous portions which exhibit opposite electric polarity when said terminals are connected in circuit with the ordinary alternating current lighting system.

In testimony whereof I hereunto affix my signature.

CERTIFICATE OF CORRECTION.

Patent No. 1,853,914.

April 12, 1932.

ORAN T. McILVAINE,

It is hereby certified that error appears in the printed specification of the above numbered patent requiring correction as follows: Page 2, line 35, for "waved" read wave a; and that the said Letters Patent should be read with this correction therein that the same may conform to the record of the case in the Patent Office.

Signed and sealed this 12th day of July, A. D. 1932.

M. J. Moore,
Acting Commissioner of Patents.
